Ch. Parker Attorney

UNITED STATES PATENT OFFICE.

CHARLES G. LACY, DECEASED, LATE OF ALLIANCE, OHIO; BY LYDIA LACY, ADMINISTRATRIX, OF ALLIANCE, OHIO.

PLASTIC-MATERIAL FURNACE.

1,392,181.

Specification of Letters Patent. Patented Sept. 27, 1921.

Application filed October 7, 1920. Serial No. 415,427.

To all whom it may concern:

Be it known that CHARLES G. LACY, deceased, late a citizen of the United States, residing at Alliance, in the county of Stark and State of Ohio, had invented certain and new and useful Improvements in Plastic-Material Furnaces, of which I, LYDIA LACY, a citizen of the United States, and resident of Alliance, Ohio, administratrix of the estate of said CHARLES G. LACY, declare, to the best of my knowledge and belief, the following is a specification.

The invention relates to apparatus for heating plastic material, such as cement mortar, lime mortar, or the like, so that the same may be properly worked.

An important object of the invention is to provide apparatus of the above mentioned character, which is so constructed that the same is particularly well adapted to be used in a building, the walls of which are to be plastered, for holding and heating a plastic material, in a manner whereby it may be conveniently worked by the mason with the trowel in the ordinary manner.

A further object of the invention is to provide means which are convenient in use, to securely detachably lock the top or tray of the apparatus to the furnace or heater portion.

A further object of the invention is to provide apparatus of the above mentioned character, which is simple in construction, inexpensive to manufacture, strong, and durable.

Other objects and advantages of this invention will be apparent during the course of the following description.

In the accompanying drawings forming a part of this specification and in which like numerals are employed to designate like parts throughout the same,

Figure 1 is a side elevation of apparatus embodying my invention,

Fig. 2 is a central longitudinal sectional view through the same,

Fig. 3 is a plan view of the same,

Fig. 4 is a horizontal sectional view taken on line 4—4 of Fig. 1,

Fig. 5 is a detail sectional view taken on line 5—5 of Fig. 3, and,

Fig. 6 is a plan view of a removable head or cover,

Fig. 7 is a view of a portion of the appa-

ratus, similar to Fig. 2, showing the cover removed.

In the drawings, wherein for the purpose of illustration is shown a preferred embodiment of my invention, the numeral 10 designates a preferably cylindrical shell or casing, constituting the fire-box of the heater. This shell is preferably formed of sheet metal and has its lower end closed by a grate 11, having draft openings 12, as shown. This grate is supported by L-shaped straps 13, secured to the lower end of the shell 10, as shown.

The fire-box shell 10 is supported by upstanding or vertical strap-legs 14, arranged upon the outer side thereof and secured thereto by means of bolts or rivets 15, as shown. At the lower ends these strap-legs have their material preferably bent to form open triangular feet 16, as shown. An ash collecting tray 17 is arranged below the grate 11 to catch the ashes and is connected with the upper ends of the feet 16, by means of bolts or rivets 17', as shown.

Near its lower end the fire-box shell 10 is provided with an opening 18, serving as a draft opening and as an opening for the insertion of a poker or the like to stir the fire. A laterally extending tray 19 is secured to the fire-box shell 10 below and adjacent the opening 18, to catch the ashes or coals passing from the opening when the fire is being stirred, as above stated.

At their upper ends the strap-legs 14 have their material bent to form upwardly diverging hollow triangular heads 20, embodying upper horizontal portions 21. The lower ends 22 of these hollow heads are secured to the body portions of the strap-legs 14 by certain of the bolts or rivets 15, as shown.

The numeral 23 designates a plastic material heating and supporting tray, preferably formed of sheet metal, with three of its edges bent upwardly, as shown at 24, and one edge bent downwardly, as shown at 25, whereby the plastic material will be properly retained upon the tray and yet may be scraped off of the same. This heating tray is provided upon its lower side with diagonally arranged strips or bars 26, crossing each other and attached to the tray 23 by bolts or rivets 27. The open triangular heads 20 are so arranged that they are

adapted to engage with the diagonal strips or bars 26, to securely hold the tray upon the same, against longitudinal movement in either direction.

- 5 Means are provided to detachably lock the tray 23 to the open triangular heads 20, against vertical movement with relation thereto, comprising a plurality of L-shaped bolts 28, rigidly mounted upon a shifting 10 ring 29, adapted to be turned by a handle or crank 30. This shifting ring slidably engages the lower surface of the tray 23 and is held thereto by sockets 31 formed in the strips or bars 26, as shown. It is obvious 15 that by turning the shifting ring 29 in one direction the bolts 28 will be moved into the open triangular head 20 in engagement with the horizontal portions 21 thereof.

The numeral 32 designates a cover, preferably formed of sheet metal, which may be arranged upon the upper end of the fire-box shell 10, if desired, to regulate the heat being imparted to the tray 23. This cover is provided with a handle 33 as shown.

- 25 In the use of the apparatus, the fire is built in the fire-box 10, and the plastic material placed upon the heating tray 23, whereby the same is retained at the proper temperature. When the apparatus is not in use, or for the purpose of cleaning the same, the tray 23 may be removed from the hollow triangular heads 20, the same being conveniently accomplished by turning the shifting ring 29 in the direction to withdraw the 30 bolt 28 from within the triangular heads 20.

35 It is to be understood that the form of the

invention herewith shown and described is to be taken as a preferred example of the same, and that various changes in the shape, size, and arrangement of parts may be resorted to without departing from the spirit of the invention or the scope of the subjoined claim.

Having thus described the invention, I claim:—

45 In apparatus of the character described, an upstanding fire-box shell, upstanding strap-legs secured thereto and extending upwardly and downwardly beyond the same and having their upper ends bent to form 50 substantially triangular open heads embodying horizontal portions, a tray adapted to be arranged upon the horizontal portions of the triangular open heads, straps crossing each other and diagonally arranged upon the 55 lower surface of the tray and rigidly secured thereto for engagement with the triangular heads, said straps having sockets formed therein, and a shifting ring mounted within the sockets and carrying laterally extending 60 bolts adapted to enter the triangular heads for engagement with the horizontal portions thereof.

In testimony whereof I affix my signature in the presence of two witnesses.

LYDIA LACY,
Administratrix of said Charles G. Lacy, deceased.

Witnesses:

SYLVIA BORON,
E. L. SNYDER.
